SIDE DOOR CONSTRUCTION

Kenneth J. Tobin, Chicago, Ill., assignor, by
mesne assignments, to The Youngstown Steel
Door Company, Cleveland, Ohio, a corporation
of Ohio

Application February 1, 1932, Serial No. 590,022

13 Claims. (Cl. 20—22)

This invention relates to side door construction utilized upon freight cars and concerns itself primarily with the auxiliary door of the double door construction of automobile freight cars and, more particularly, with the post structure employed upon such auxiliary doors.

It is an object of this invention to provide a side door for freight cars having a jamb or post mounted for swinging movement thereon.

10 Another object is the provision of a side door having a post swingingly mounted adjacent the forward edge of said door and adapted to lock said door in closed position.

Another object is the provision of a car side door provided with a swinging post adapted for engagement with upper and lower portions of said car whereby said post serves both as a tie and as a strut for said car in a predetermined position of the door.

20 An object, also, is the provision of a car side door having a post releasably mounted for swinging movement thereon.

It is a further object of this invention to provide a side door having secured thereto a post or jamb which is readily removable from the door, whereby said door may be removed from the car without the necessity of removal of the supporting track for said door.

25 A further object is the provision of a side door having a swinging post, brackets being secured to said door and said post, respectively, for supporting the post upon the door, said brackets serving to limit the angular displacement of said post.

30 A further object is the provision of a post mounted upon a side door for swinging movement in a plane parallel to the door, the post in its projected or operative position securing the door against transverse and longitudinal movements relative to the car.

Another object is the provision of a swinging post for side doors serving to reinforce said doors against bulging stresses.

Further objects will become apparent as the 45 description of the invention proceeds.

In the drawings

Figure 1 is a partial longitudinal sectional view looking at the side double doors of a freight car from the inside of said car and illustrating a 50 swinging post in various positions in the closed and open positions of the door upon which the post is mounted.

Figure 2 is an end view of an auxiliary door having a post or jamb applied thereto, looking to the right as viewed in Figure 1.

Figure 3 is an enlarged sectional view taken on line 3—3 of Figure 1.

Figure 4 is an enlarged sectional view taken on line 4—4 of Figure 3.

Figure 5 is a vertical section taken on line 5—5 of Figure 6.

Figure 6 is a partial horizontal section taken on line 6—6 of Figure 2.

Figure 7 is an enlarged elevation of the upper keeper, a part of the upper post casting being 10 illustrated.

Figure 8 is a horizontal section on line 8—8 of Figure 1.

Figure 9 is a horizontal section on line 9—9 of Figure 1.

Figure 10 is an enlarged elevation of the lower keeper and showing a portion of the lower post casting and locking bolt in position therein.

Figure 11 is a view similar to Figure 3 illustrating a modified construction.

Figure 12 is a partial elevation of the structure shown in Figure 11 as viewed from the left of said figure.

Figure 13 is a view similar to Figure 6 on an enlarged scale.

Figure 14 is a side elevation of a part of the mounting shown in Figure 11 which is secured to the post or jamb.

Figure 15 is a front elevation of the structure shown in Figure 14.

Figure 16 is a side elevation of a part of the mounting shown in Figure 11 which is secured to the door.

Figure 17 is a front elevation of the structure shown in Figure 16.

In loading automobiles or other bulky lading into railway freight cars the sides of these cars are provided with openings which are exceptionally wide and which are covered by means of two sliding doors, these doors in their opening movement traveling in opposite directions. The exceptional width of door opening leaves quite a large unsupported span substantially in the center of the sides of the cars. In order to reinforce the sides of the cars in the door openings reinforcing posts or jambs have been utilized, which posts or jambs are customarily applied to one of the double door, usually designated the auxiliary or supplemental door. In the closed position of this door the post or jamb is 50 interlocked with the sub-structure and superstructure of the car in order to tie these parts together to prevent their spreading when the car is subjected to impact and, furthermore, to serve as a strut to avoid relative movement of these 55

parts toward each other. The jambs or posts heretofore employed have been of two kinds, namely, jambs which have been rigidly secured to the supplemental door for movement therewith and those which are capable of movement independently of the supplemental door. The latter type of jamb or post, because of its loss from the car, has proved unsuccessful. The post or jamb which is secured to the door for movement therewith has in the main been satisfactory for the purpose indicated above and, also, for relieving the supplemental door to which the post or jamb is secured from stresses tending to bulge said door outwardly. With the latter type of post or jamb, however, it has been found to be impossible to remove the supplemental door from the car side or to remove the post or jamb from the door without first taking off the track upon which the door is supported or removing the supporting hangers or the top retainer customarily employed with said door. According to the instant invention there is provided a jamb or post construction for the supplemental door of a double door freight car capable of serving both as a strut and as a tie for said door, which is readily applicable and releasable from the door, which serves as a reinforcement for the door against bulging stresses and which, upon removal from the door, permits said door to be slid off the track without disturbing the track or fixtures applied to the car and to the door with the exception of the stops for the door.

Referring to the embodiment of the invention illustrated in Figures 1 to 10, inclusive, there is disclosed a railway house car 10 having exceptionally large door openings provided in the sides thereof, each of which openings is adapted to be closed by a plurality of sliding doors consisting of a main door 11 and an auxiliary door 12. As illustrated in the drawings these doors preferably are formed of metal and are provided with a plurality of corrugations 13 and 14, although it is to be understood that the invention is applicable to doors of construction other than that shown. Each of the doors is provided with a plurality of hangers 15 adapted to support the door for sliding movement upon a track 16. The upper margin of the door is retained against outward movement from the car by means of a retaining bar 17.

The jamb or post 18 of the instant invention is mounted upon the auxiliary door 12 adjacent the forward edge thereof. Mounting of said jamb or post is effected by means of a bracket member 19 secured to the jamb and cooperating with a bracket member 20 fastened to the door 12. The bracket member 19 comprises a base portion 21 by which the bracket is adapted to be secured to the jamb and the projecting hollow boss 22. The bracket member 20 secured to the door is provided with flanges 23 by means of which said bracket is secured to the door and with a projecting hollow lug 24 adapted to be received within the hollow boss 22 provided on the jamb bracket member. Extending preferably at right angles from the lug 24 provided on the door bracket member is a lobe 25 adapted in the operative assembly of the two bracket members to be positioned within the hollow boss 22 formed on the jamb bracket member. An extension 26 is provided on the bracket member 19, this extension in the projected position of the jamb when the supplemental door is closed having overlapping relationship with the bracket member 20 secured to the door. It will be observed

from a consideration of Figure 4 of the drawings that an opening 27 elongated preferably in the direction of the height of the jamb is provided in the bracket member 19. Moreover, the height of the opening 27 is slightly greater than the combined width of the lug 24 and the lobe 25 provided on said lug. It will be apparent from the construction of the means employed to mount the jamb or post upon the supplemental door that by positioning the jamb in a substantially horizontal plane after the jamb bracket member and the door bracket member have been secured in proper position engagement between the boss 22 and lug 24 may readily be effected. After such engagement the jamb may be locked in position upon the door by rotation of said jamb through an angle of ninety degrees so that it assumes a substantially vertical position. Disengagement of the bracket members, and consequently of the jamb from the door, will then be avoided because of the engagement of the lobe 25 within the boss 24 provided on the jamb bracket member. As a further protective measure it is preferred that a rivet 28 passing through the jamb, the door and the boss and lug provided on the bracket members be employed to prevent disengagement of the jamb from the door. It will be apparent, furthermore, from a consideration of Figures 1 and 6 of the drawings that the jamb may readily be rotated in a counterclockwise direction as viewed in Figure 1 but that its rotation in a clockwise direction will be resisted by engagement of the projection 26 formed on the jamb bracket member and the bracket member 20 secured to the door.

In order to lock the jamb and consequently the door to which it is applied in closed position keepers 29 and 30 are provided. The keeper 29 is secured to the car above the jamb while the keeper 30 is secured to the car below the jamb. The keeper 29 is provided with a base or attaching portion 31 from which depends a portion having a latch receiving recess 32. The latch receiving recess is open at one end as indicated at 33 and the opposite end thereof is provided with an abutment wall 34. Extending inwardly in the recess are a plurality of horizontally positioned flanges 35 and 36.

The keeper 30 secured below the door jamb is provided with a base or attaching portion 37 from which extends in offset relation thereto a latch receiving recess 38. As clearly shown in Figure 9 of the drawings the latch receiving recess is open at one end as indicated at 39 and closed by means of a wall 40 at its opposite end. Inwardly directed flanges 41 and 42 extend into the latch receiving recess 38. The lower keeper 30 is provided additionally with a bolt receiving recess 43 which is approached by means of an inclined wall 44.

The jamb 18 is preferably provided at its upper and lower ends with latches 45 and 46, respectively. Each of these latches is provided with an enlarged head as indicated at 47 and 48 which, in the projected position of the jamb, are adapted to be seated within the latch receiving recess of their respective keepers in overlapping relationship with the inwardly directed flanges provided on said keepers. The lower end of the jamb is additionally provided with a locking bolt 49 mounted upon the jamb by means of a bracket member 50 within which the bolt is capable of reciprocable movement. The lower end of the locking bolt in the projected position of the jamb

is adapted to be received within the bolt receiving recess 43 provided in the lower keeper 30.

It will be apparent from the foregoing detailed description that when the supplemental door is in its closed position and the jamb or post mounted upon said door is in the projected or locking position that said jamb through the latches 45 and 46 will have locking engagement with the keepers 29 and 30 mounted, respectively, above and below said jamb. In such locking engagement the enlarged head portions on the latches 45 and 46 will lie in overlapping relationship with the inwardly directed flanges provided on the keepers. Additionally, the locking bolt 49 will assume its projected position and lie within the bolt receiving recess 43 provided in the lower keeper. It is evident that the supplemental door is incapable of movement either longitudinally or transversely of the car. Moreover, the overlapping relationship of the enlarged heads provided on the latch members secured to the jamb and the inwardly directed flanges provided on the keepers will tie together the upper and lower parts of the car within the door opening and the jamb, which is clearly illustrated as a sturdy member, will resist tendency of the upper and lower parts of the car at the door opening from approaching each other. It is also clear that the pressure of lading within the car against the jamb will be resisted by the jamb without transmitting said pressure to the door. In order to release the door for sliding movement toward its open position the locking bolt 49 is retracted and the jamb or post is swung in a counter-clockwise direction as viewed in Figure 1 until said jamb clears the keepers. The supplemental door may then be moved to its open position. In such position the jamb will assume its normal vertical position. In the closing movement of the supplemental door the jamb will again be swung to the position indicated in Figure 1 and the door moved to its closed position. The jamb is then swung to vertical position, whereby the latches provided on the jamb will operatively engage the keepers provided on the car. During this swinging movement of the jamb the lock bolt 49 will engage the inclined wall 44 provided on the lower keeper and will automatically be raised so that when the jamb takes its final closing position said locking bolt will drop into the bolt receiving recess 43.

In Figures 11 to 17, inclusive, of the drawings there is disclosed a further embodiment of another preferred form of the instant invention. The jamb or post 18 is provided with a bracket member 51 secured thereto through the flanges 52. The bracket member 51 is provided with a base portion 53 from which extends a cylindrical boss 54, the end of which is preferably formed with an angular extension 55. Secured to the door exteriorly thereof is a bracket member 56 having the attaching flanges 57 from which extends a hollow housing member 58. In the mounting of the jamb or post 18 upon the supplemental door 12 disclosed in Figure 13 of the drawings the cylindrical boss 54 formed on the jamb bracket member 51 extends through the door and within the hollow housing member 58 formed on the bracket member 56. Engagement between the bracket members is effected when the jamb is in substantially horizontal position so that registry between the flange 55 provided on the boss 54 with the recess in the housing member 58 is had. The jamb is then rotated through an angle of ninety degrees until it assumes a sub-

stantially vertical position whereupon the flange 55 will extend across the recess provided in the housing member 58 and engage the wall thereof so as to prevent release of the jamb from the door. This fact is clearly illustrated in Figure 12 of the drawings. It is preferred, in order to avoid accidental disengagement of the jamb from the door, to employ a rivet 59 extending through the door, the jamb and the bracket members as clearly shown in Figure 13 of the drawings. It will be clear that the jamb is mounted upon the door in the instant embodiment of the invention for swinging movement relative thereto. The construction of the jamb may be similar and its locking engagement with the door the same as in the first embodiment of the invention disclosed. In the embodiment of the invention considered, however, it will be apparent that by taking out the rivet 59 and disengaging the jamb from the door the rear or inward surface of the door is substantially plane so that no obstacle is presented upon the door which may engage the rear door post 60 in the opening sliding movement of the door. In view of this fact the door in such sliding movement may be disengaged from the car without the necessity of removing the door or car fixtures.

It is apparent that numerous modifications and changes may be effected in the embodiments of the invention disclosed without departing from the spirit thereof. It is intended, consequently, that all such modifications and changes be comprehended within the invention, which is to be limited only by the scope of the appended claims.

I claim:

1. A railway house car having a door opening, a main door, a supplemental door, said doors adapted to close said opening and having sliding movement in opposite directions in the opening travel thereof, a jamb for said auxiliary door, said jamb being mounted on the door interiorly of said car for swinging movement parallel to the door.

2. A railway house car having a door opening, a main door and an auxiliary door closing said opening, and having sliding movement in opposite directions in the opening travel thereof, a post mounted upon said auxiliary door interiorly of the car for swinging movement parallel to said door and keepers secured to said car above and below said post for engaging said post in a predetermined position thereof.

3. A railway house car having a door opening, a main door and an auxiliary door closing said opening, and having sliding movement in opposite directions in the opening travel thereof, a post mounted upon said auxiliary door interiorly of the car for swinging movement parallel to said door and keepers secured to said car above and below said post for engaging said post in a predetermined position thereof, and means locking said post against swinging movement.

4. In combination, a sliding door, a jamb, bracket means carried by said door and said jamb, said bracket means being releasably interlocked and retaining said jamb for swinging movement parallel to said door.

5. A railway car having a side door opening, a pair of sliding doors for closing said opening, a jamb for cooperating with said doors, a bracket secured to said jamb, a bracket secured to one of said doors in operative engagement with said first mentioned bracket and means connecting said brackets together whereby said jamb is movable with said door, said jamb bracket being

tatably engaged with said door bracket whereby said jamb is capable of swinging movement in a plane parallel to said one door.

6. A railway car having a side door opening, a pair of sliding doors for closing said opening, a jamb for cooperating with said doors positioned inwardly thereof, a bracket secured to said jamb provided with a boss, a bracket secured to said door having a recess for receiving said boss to swingably mount said jamb, said boss having a lug engageable with said door bracket to prevent disengagement of said jamb from the door in the normal position of said jamb.

7. A railway car having a side door opening, a pair of sliding doors for closing said opening, a jamb for cooperating with said doors, a bracket secured to said jamb, a bracket secured to one of said doors, said brackets having operative engagement for mounting said jamb for swinging movement in one direction upon said door and means provided on said brackets engageable to prevent swinging movement of said jamb in the opposite direction.

8. An auxiliary sliding car door for the double door construction of automobile freight cars comprising a jamb mounted for swinging movement in a plane parallel to said door upon the interior forward margin of said door.

9. A railway house car having a side door opening, a pair of doors for closing said opening, a longitudinally movable jamb cooperating with said doors, said jamb being mounted upon the forward margin of one of said doors interiorly thereof for swinging movement in a plane parallel to said one door and means carried by said car above and below said jamb for engagement therewith in a predetermined position of the jamb to tie said car together at said opening.

10. A railway car having a side door opening, a pair of sliding doors for closing said opening, a jamb adapted to be mounted upon the forward margin of one of said doors, means for mounting said jamb, said means comprising a bracket secured to said jamb, a bracket secured to said one door outwardly thereof, said brackets having ro-

tatable interlocked engagement whereby said jamb is movable with said door and capable of swinging movement in a plane parallel thereto.

11. A railway car having a side door opening, a pair of sliding doors for closing said opening, a jamb for one of said doors and cooperating means having interlocking engagement securing said jamb upon one of said doors for swinging movement in a plane parallel to said one door, said jamb being removable from said door when swung to a predetermined position to release said interlocking engagement.

12. A railway car having a side door opening and a fixed post adjacent said opening, a pair of oppositely sliding doors for closing said opening, a track secured to said car for supporting said doors for sliding movement, one of said doors having an inner surface disposed outwardly of said fixed post, a jamb for said one door and means connected to said jamb for securing said jamb to said inner surface of said door at the forward margin thereof for swinging movement in a plane parallel to said one door, said jamb being aligned with said fixed post, said jamb and said means being removable from said door when said jamb has been turned to a predetermined position whereby said one door may be slid past said fixed post to permit removal of said one door.

13. A railway car having a side door opening and a fixed post adjacent said opening, a pair of oppositely sliding doors for closing said opening, a track secured to said car for supporting said doors for sliding movement, one of said doors having an inner surface disposed outwardly of said fixed post, a jamb for said one door, means for securing the said jamb upon said inner surface of said door at the forward margin thereof for swinging movement in a plane parallel to said one door, said jamb being aligned with said fixed post, said jamb being removable from said door whereby said door presents an unobstructed inner surface permitting removal of said door by sliding movement thereof on said track past said fixed post.

KENNETH J. TOBIN. 45
